CLAIM

We claim the ornamental design for a spa shell, as shown and described.

DESCRIPTION

FIG. 1 is a top front perspective of a spa shell showing our new design, the broken lines are for illustrative purposes only and form no part of the claimed design;

FIG. 2 is a top plan view of the spa shell of FIG. 1;

FIG. 3 is a cross-sectional view taken along line 3—3 of FIG. 2; and,

FIG. 4 is a cross-sectional view taken along line 4—4 of FIG. 2;

FIG. 5 is a cross-sectional view taken along line 5—5 of FIG. 2;

FIG. 6 is a cross-sectional view taken along line 6—6 of FIG. 2; and,

FIG. 7 is a cross-sectional view taken along line 7—7 of FIG. 2.

The bottom is plain and unornamented.
